UNITED STATES PATENT OFFICE

124,260

DESIGN FOR A SAFETY HOISTING HOOK

John T. Rice, Brooklyn, N. Y.

Application June 17, 1940, Serial No. 93,060

Term of patent 7 years

To all whom it may concern:

Be it known that I, John T. Rice, a citizen of the United States, residing at Brooklyn, in the county of Kings and State of New York, have invented a new, original, and ornamental Design for a Safety Hoisting Hook, of which the following is a specification, reference being had to the accompanying drawing, forming part thereof.

Figure 1 is a side elevational view of a safety hoisting hook with the sliding gate in a closed position: and

Figure 2 is a side elevation of the same with the sliding gate in an open position, showing my new design.

The hook is round in cross section.

I claim:

The ornamental design for a safety hoisting hook, substantially as shown and described.

JOHN T. RICE.
